UNITED STATES PATENT OFFICE

2,258,496

AIR SEPARATOR

Robert J. Jauch and Samuel E. Gilmore, Fort Wayne, Ind., assignors to The Wayne Pump Company, Fort Wayne, Ind., a corporation of Maryland

Application March 24, 1939, Serial No. 264,012

5 Claims. (Cl. 183—2.5)

This invention pertains to liquid dispensing apparatus and more particularly to air separation and recovery means therefor.

It is an object of this invention to provide a liquid dispensing apparatus having an air separator which is efficient in operation wherein high and low pressure chambers are provided for separation and recovery purposes.

Another object is to provide air separating means which only operates to vent the separated air to atmosphere after a predetermined pressure is built up in the separator.

Yet another object is to provide air separating means and recovery means therefor which is only effective after the pump is pumping solid liquid.

Still another object is to provide means for positively removing recovered liquid from an air separator.

A further object is to provide air separating means which is so constructed and arranged that liquid cannot be ejected therefrom under any conditions.

With these and various other objects in view, the invention may consist of certain novel features of construction and operation as will be more fully described and particularly pointed out in the specification, drawings and claims appended hereto.

In the drawings, which illustrate an embodiment of the device and wherein like reference characters are used to designate like parts—

Figure 1 is an elevation, partly in section, of a liquid dispensing apparatus embodying the invention;

Figure 2 is a fragmentary side elevation, partly in section, of the liquid dispensing apparatus illustrated in Figure 1, the same looking toward the left as viewed in said figure;

Figure 3 is an enlarged sectional elevation of the pump and air separator shown in Figures 1 and 2;

Figure 4 is an enlarged top plan view of the pump shown in Figure 3;

Figure 5 is an enlarged sectional elevation of the pump illustrated in Figure 4;

Figure 6 is an enlarged sectional top plan view taken through the pump control valve mechanism for the air separator;

Figure 7 is an enlarged sectional elevation taken substantially in the plane as indicated by the line 7—7 of Figure 6.

In the liquid dispensing apparatus shown, the base 10 provides a support for the casing 12 within which the pump 14 is supported, said pump being of the positive displacement rotary type

provided with the inlet 16 adapted to be connected to a source of liquid supply (not shown). The outlet or pressure side of the pump is connected through the pipe 18 to the inlet 20 of the air separator 22, said air separator being provided with the vent 24 extending to and vented to atmosphere at a point high in the pump casing. The outlet 26 of the air separator is connected to the inlet side 28 of the meter 30 shown as of the positive displacement type. Said meter is provided with the meter shaft 32 adapted to be connected and operate a registering and computing mechanism 34 which may be as shown in Patent No. 2,151,239, Sliye et al., granted March 21, 1939. The register of said registering mechanism is adapted to be reset through the reset shaft 36 by means of the crank 38, an extension of said reset shaft being provided with the interlock mechanism 40 for preventing dispensing until the register has been reset to zero subsequent to each dispensing operation. The outlet side of the meter 30 is connected to the upwardly extending pipe 42 whereby liquid is supplied to the sight gauge 44 which may be of the type such as shown in Patent No. 2,157,087, Jauch et al., granted May 2, 1939. The outlet side of the sight gauge 44 is connected to the pipe 46 to which the hose 48 is connected. The opposite end of the hose is connected to the nozzle 50 controlled by the nozzle valve 52, said nozzle valve 52 being adapted to be operated by means of the lever 54 pivoted as at 56 within the guard 58. The guard 58 is adapted to provide a support for the nozzle on the fixed support 60, and when in supported position the nozzle and lever are so arranged that the nozzle valve cannot be operated.

When inoperative position the nozzle is also supported so that the end thereof projects into a boot (not shown) whereby the end of the nozzle is not accessible until the nozzle is removed from its support. A guard lever 62 is pivoted on the casing as at 63 and is adapted to overlie the pushbutton 64 disposed above the fixed support, the pushbutton upon being moved inwardly by placing the nozzle on the hook, or manually, causing the bellcrank 66 to be moved in a counter-clockwise direction about the pivot 68 to depress the switch rod 70, said rod being connected to the switch 72 of the motor 74 to move the switch to open position when the rod is depressed.

The motor is provided with the pulley 76 adapted to operate the pump 14 by movement of the belt 78 which also engages the pump pulley 80. The bell crank 66 is likewise adapted to be moved by the pushbutton 82 disposed be-

low the fixed support. When the nozzle is removed from the support the pushbutton 82 may be moved inwardly to cause the bellcrank to be moved in a clockwise direction to close the switch, the bellcrank being connected to the interlock as at 84 which prevents movement of the bellcrank to open the switch unless the register of the computing mechanism 34 has been reset to zero after each dispensing operation.

The pump 14, as has already been stated, is shown as a positive displacement pump and is provided with the inlet chamber 86 in direct communication with the inlet 16. The inlet chamber 86 is in communication with the suction chamber 88 through the removable screen or filter 90 and a rotor 92 is provided on the operating shaft 94 on which the pulley 80 is disposed. The rotor 92 is disposed between the suction chamber 88 and the pressure chamber 96 which is in communication with the pipe 18. The shaft 94 is provided with the spaced bearings 98 and 100 and the pump housing adjacent one end is closed as at 102, and the opposite end of the shaft passes through a suitable stuffing box 104 for attachment to the pulley 80.

The valve housing 106 is disposed on the pump housing and said valve housing is provided with the connection 108 to the pump suction, and provided with the connection 110 to the pump discharge. The connection 108 communicates with the valve recess 112 in which the sleeve valve 114 is slidably mounted, said sleeve valve being provided with the circular depression 118 and the axial channel 120, said channel communicating with the piston housing 122 through the ports 124 whereby the pump suction is in communication with one side of the piston 126. The piston 126 is connected to the sleeve valve stem as at 128 and is provided with the leathers 130 spring pressed as at 132, the springs being held by means of the retainer 134, said piston being normally urged toward the pump discharge by means of the spring 136, the stop 138 on the closure 140 limiting the movement of the piston. The piston thus is adapted to be acted upon by the pump pressure and the pump suction. The housing is provided with the aperture 142 which is in communication as at 144 with the return 146. The aperture 142 is adapted to connect the return 146 to the pump suction through suitable radial apertures 148 disposed around the depressed portion 118 of the sleeve valve, the channel 120 and the connection 108. The pump is also provided with the by-pass valve 150 normally urged to closed position by means of the spring 152, said by-pass valve being adapted to open at a predetermined pressure to by-pass the liquid within the pump casing.

The air separator 22 consists essentially of the receiving or high pressure chamber 154 provided with said inlet 20 and said outlet 26, a suitable baffle 156 being provided for directing the liquid in a predetermined path. The chamber is provided with a restricted opening 158 disposed adjacent the top thereof, said opening being in communication with the low pressure, float or recovery chamber 160, said chamber being closed by means of the cap 162. The cap 162 is provided with the valve 164 normally closed by means of the spring 166, the valve controlling the exhaust from the float chamber 160 to the vent pipe 24, the spring being set at a predetermined pressure so that the valve is only opened after a predetermined pressure is built up in the float chamber whereby the vapor passing over into the

float chamber will precipitate the liquid in said float chamber. The lever 168 is pivoted as at 170 to the support 174, and a valve 176 is provided for closing the restricted opening after a predetermined liquid level is reached in the chamber 160. The float 178 is pivoted as at 180 to the lever for controlling movement thereof as determined by the liquid level in the float chamber. The float may be provided with the guide rod 182 suitably guided as at 184 for insuring the proper vertical movement of said float. The recovery line 146 is connected as at 186 to the float chamber and extends to and is connected to the valve housing 106 as already described.

In the operation of this form of the device, when it is desired to dispense liquid, the hose nozzle 50 is removed from the support 60. The button 82 is moved inwardly, assuming the register to have been set to zero position, starting the motor. The motor will cause operation of the pump to supply liquid to the air separator, the liquid passing through the air separator into the meter and outwardly of the discharge line 42, sight gauge 44, line 46, hose 48, and through the nozzle 50, it being assumed that the nozzle valve 52 is opened.

The liquid supplied to the high pressure chamber 154 of the air separator will receive a swirling motion releasing any entrained air or vapor which will pass through the restricted opening 158. The liquid entrained in the vapor will be deposited in the recovery chamber 160, and the liquid level will rise as the sleeve valve 114 will be closed so long as any air is being pumped. When the pump is pumping solid liquid the suction acting on the left side of the piston 126, in addition the pressure of the pump acting on the opposite side of the piston 126, will cause the piston to be moved toward the left as viewed in Figure 6, which in turn will cause the depressed portion 118 and the apertures 148 to register with the opening 142, permitting liquid to be recovered from the chamber 160 to the suction side of the pump.

After the predetermined amount of liquid is trapped in the recovery chamber, and in the event the liquid is not exhausted quickly enough, as for example, where there is a surge of liquid into the recovery chamber, the float will cause the valve 176 to close, thus preventing liquid from being ejected through the vent tube 24. After a predetermined pressure has been built up in the recovery chamber 160 the valve 164 will open to exhaust the air to the atmosphere, the pressure previously built up in the float chamber insuring that all the liquid will be precipitated for recovery purposes. The valve 164 being a normally closed valve will prevent air from the atmosphere being received into the pump, and with the arrangement of the valves 176, 164 and 114, a device is provided which is equally effective on any lifts.

It is to be understood that we do not wish to be limited by the exact embodiment of the device shown, which is merely by way of illustration and not limitation, as various and other forms of the device will of course be apparent to those skilled in the art without departing from the spirit of the invention or the scope of the claims.

What is claimed is:

1. In combination, a pump having a suction side and a pressure side, the inlet being on said suction side and being adapted to be connected to a source of liquid supply, the outlet being on

the pressure side, an air separator having a main and secondary chamber, said main chamber having an inlet and an outlet, said last named inlet being connected to the outlet of said pump, a connection between said main and secondary chambers including a restricted opening, a valve in said secondary chamber for controlling said opening, a float for said valve in said secondary chamber for closing said valve after a predetermined amount of liquid is contained in said secondary chamber, a vent to the atmosphere from said secondary chamber, a predetermined pressure set valve controlling said vent, and means for controlling discharge from said secondary chamber.

2. In combination, a pump having a suction side and a pressure side, the inlet being on said suction side and being adapted to be connected to a source of liquid supply, the outlet being on the pressure side, an air separator having a main and secondary chamber, said main chamber having an inlet and an outlet, said last named inlet being connected to the outlet of said pump, a connection between said main and secondary chambers including a restricted opening, a valve in said secondary chamber for controlling said opening, a float for said valve in said secondary chamber for closing said valve after a predetermined amount of liquid is contained in said secondary chamber, a vent to the atmosphere from said secondary chamber, a predetermined pressure set valve controlling said vent, means for controlling discharge from said secondary chamber, said last named means including valve mechanism provided on said pump having a suction connection to the suction side of said pump, a valve for controlling said suction connection, means associated with said last named valve and in communication with the suction and pressure sides of said pump, said last named means being moved by the suction and pressure when the pump is pumping solid liquid to open said last named valve, and a connection between said suction connection and said secondary chamber for returning liquid to the suction side of said pump when said last named valve is opened.

3. In combination, a pump having a suction side and a pressure side, the inlet being on said suction side and being adapted to be connected to a source of liquid supply, the outlet being on the pressure side, an air separator having a main and secondary chamber, said main chamber having an inlet and an outlet, said last named inlet being connected to the outlet of said pump, a connection between said main and secondary chambers including an opening, a valve controlling said opening, said valve being controlled by liquid supplied to said secondary chamber, a vent to atmosphere from said secondary chamber,

5 a discharge from said secondary chamber connected to said pump, a predetermined pressure set valve controlling said vent, and valve mechanism controlled by said pump for controlling said discharge.

4. In combination, a pump having a suction side and a pressure side, the inlet being on said suction side and being adapted to be connected to a source of liquid supply, the outlet being on the pressure side, an air separator having a main and secondary chamber, said main chamber having an inlet and an outlet, said last named inlet being connected to the outlet of said pump, a connection between said main and secondary chambers including a restricted opening, a valve in said secondary chamber for controlling said opening, means responsive to the level of liquid in said secondary chamber for closing said valve after a predetermined amount of liquid is contained in said secondary chamber, a vent to the atmosphere from said secondary chamber, a predetermined pressure set valve controlling said vent, and means for controlling discharge from said secondary chamber.

25 5. In combination, a pump having a suction side and a pressure side, the inlet being on said suction side and being adapted to be connected to a source of liquid supply, the outlet being on the pressure side, an air separator having a main and secondary chamber, said main chamber having an inlet and an outlet, said last named inlet being connected to the outlet of said pump, a connection between said main and secondary chambers including a restricted opening, a valve in said secondary chamber for controlling said opening, means responsive to the level of liquid in said secondary chamber for closing said valve after a predetermined amount of liquid is contained in said secondary chamber, a vent to the atmosphere from said secondary chamber, a predetermined pressure set valve controlling said vent, means for controlling discharge from said secondary chamber, said last named means including valve mechanism provided on said pump having a suction connection to the suction side of said pump, a valve for controlling said suction connection, means associated with said last named valve and in communication with the suction and pressure sides of said pump, said last named means being moved by the suction and pressure when the pump is pumping solid liquid to open said last named valve, and a connection between said suction connection and said secondary chamber for returning liquid to the suction side of said pump when said last named valve is opened.

ROBERT J. JAUCH.
